UNITED STATES PATENT OFFICE

EDGAR B. SYMONS, OF LOS ANGELES, CALIFORNIA, ASSIGNOR TO NORDBERG MANUFACTURING COMPANY, OF MILWAUKEE, WISCONSIN, A CORPORATION OF WISCONSIN

CRUSHING MACHINE

Application filed October 8, 1928. Serial No. 310,988.

My invention relates to a crushing device and particularly to a crushing device in which a cone is gyrated within the normally fixed concave or bowl. One object of my invention is to provide a liner for such concave or bowl, which shall be quickly and firmly securable in position. Another object is to provide such a liner which shall minimize the tendency of large, hard rocks or fragments to be pinched upwardly out of the crushing zone in response to movement of cone against bowl. Another object is the provision of such a liner, and securing means therefor, such securing means being protected from external wear and being remote from the line of passage of the material being crushed. Other objects will appear from time to time in the course of the specification and claims.

I illustrate my invention more or less diagrammatically in the accompanying drawings, wherein—

Figure 1 is a vertical section;

Figure 2 is a section on the line 2—2 of Figure 1; and

Figure 3 is a section on the line 3—3 of Figure 1.

Like parts are indicated by like symbols throughout the specification and drawings.

A generally indicates a crusher shaft, the means for gyrating such shaft being not herein shown and forming no part, of themselves, of the present invention. It will be understood that any suitable driving and gyrating means may be employed, as shown for example in my co-pending application No. 220,471, filed on the 19th day of September, 1927. A¹ indicates the crushing head or cone mounted on the shaft A in any suitable manner and A² a conic mantle which is held in position on the cone, for example by the securing sleeve A³. A⁴ indicates a feed limiting or distributing plate employed for this type of crusher.

If desired, the upper portion of the conic mantle may be provided with vertical channels A⁶ which are separated by ridges or projections A⁷.

B indicates the upper portion of a cylindrical frame which extends upwardly from a

base portion B¹ which may be secured as by the bolts B² to any suitable support or supports B³.

Mounted upon the upper edge B⁴ of the member B is the supporting ring C which is normally held fixed in relation to the member B, as by the coil springs C¹, bolts C² and the annular collar C³. It will be understood that the springs are aligned by the bolts C¹ and that the bolts serve to hold the collar C³ at the desired level, the springs being compressed between the lower face of the member B⁴ and the collar.

The member C includes the screw threaded portion C⁵ in mesh with similar threads C⁷ on the cylindrical member C⁸. Herein shown as integral with the member C⁸ is the upwardly and inwardly inclined bowl or concave C⁹ which is provided with a plurality of apertures C¹⁰. C¹¹ C¹¹ indicate webs, adjacent said apertures, and connected to the members C⁸ C⁹.

D generally indicates the crushing liner for said bowl or concave. It includes a lower portion D¹ the face of which is, at the cone's closest approach, equi-distant from the opposed face of the cone. D² is an intermediate portion of the liner which inclines or flares away from the opposed face of the cone. The upper portion of the liner is occupied by a plurality of steps or ridges D³. Each such ridge includes a relatively extended face D⁴ and a shorter face D⁵.

The faces D⁴ are inclined from the opposed face of the cone at angles somewhat less than the angle of the upper portion of the liner taken as a whole. The purpose of this construction is to permit the use of a crushing opening flared upwardly and outwardly at a sufficient angle, and sufficiently spaced from the opposed portion of the cone, to receive relatively large rocks or fragments for reduction. Where a wide angle is employed and where the opposed faces of cone and bowl are smooth there is with some substances, as for example boulders mixed with clay, a tendency for rocks or boulders, particularly if of rounded contour, to be pinched upwardly out of the crushing space. In other words, when the cone approaches the bowl the rock, instead of

being reduced, may be pinched or sprung upwardly out of the crushing zone. I find that the employment of circumferential ledges or ridges or steps, for example as herein shown, much reduce or even eliminate this tendency.

In order to secure the liner upon the bowl I provide a plurality of holding lugs D⁶, herein shown as hook-shaped, which project inwardly through the apertures C¹⁰. Each such lug may be aligned between two of the webs C¹¹, as shown in Figures 2 and 3. For each such lug I may employ any suitable holding member, for example the U-bolt C¹² the ends of which pass through any suitable cross-piece or cross-member, herein shown as composed of a plurality of elements or layers C¹³. The U-bolt may be drawn up, as by the nuts C¹⁴. The opposite element C¹³ may, being composed of a plurality of removable layers or shims, be adjusted as to thickness if necessary. Note that the upper edges of the web C¹¹ are inclined downwardly and inwardly toward the axis of the cone, whereby the line of tension exerted by the U-bolts 25 inclines inwardly toward the axis of the cone.

It will be realized that whereas I have described and shown a practical and operative device, nevertheless many changes may be 30 made in the size, shape, number, relation and disposition of parts without departing from the spirit of my invention. I therefore wish my drawings to be taken as in a broad sense illustrative and diagrammatic rather than 35 as limiting me to my specific showing.

The use and operation of my invention are as follows:

In crushers of the type herein shown, as described and claimed for example in my 40 prior Patents, No. 1,537,564 and No. 1,537,565, both issued on May 12, 1925, a cone is gyrated within a normally fixed bowl, the spring release of which forms no part 45 per se of the present application. Since the stroke or throw of the cone is very great, as compared to prior practice, the liner is subjected to a heavy pounding action, and satisfactory securing means therefore must be provided. I find it preferable to conceal or 50 protect the securing means and to hold them out of the line of movement of the material undergoing crushing. Hence I have apertured the bowl, to permit the passage through such apertures of securing lugs, or to permit 55 the penetration through said apertures of securing means whereby the liner is held in position without the employment of any exposed securing members. Whereas I have 60 described and shown the employment of hook-shaped lugs in connection with U-bolts, it will be understood that a wide variety of securing members may be employed and that I do not wish to be limited to the specific 65 form or forms herein shown except so far as I

limit myself specifically by the language of the claims.

In this type of crusher a very large reduction is effected at one operation and I therefore find it desirable to have a very wide opening or flare at the top of the crushing zone, in connection with a very close setting or close approach of cone to bowl at the lower portion of the cone.

When relatively large pieces are fed to the crusher, and particularly when such pieces are rounded or are wet and slippery, as is the case when boulders mixed with clay are being crushed, there is a tendency, in earlier crushers of this type, for such boulders to be pinched or squeezed out of the crushing zone.

In such case they may pop up out of the top of the crushing zone, when nipped between cone and bowl, without being crushed or reduced. In order to prevent this action I have formed the upper face of the liner of the bowl with a series of steps or with a series of annular projections or channels. Each such step D⁴ is of sufficient area or width to grip the large boulder between itself and the cone

and is at such an angle that the boulders when so gripped will not be squeezed or pinched upwardly out of the crushing zone. Were the entire face of the bowl formed at a similar angle, the upper portion of the crushing zone would be needlessly restricted, and would be made so small, in fact, as to reduce the size of piece which could be taken, and therefore the extent of reduction which can take place at one step. However, by

widely flaring the bowl and liner and by forming the upper face of the liner with a series of steps or channels, I obtain the advantageous effect of a smaller angle between bowl and cone, while retaining the advantage of a wide flare or opening at the upper portion of the crushing zone.

I claim:

1. In a crushing machine which includes a cone, a bowl about said cone, and means for imparting a gyratory movement to said cone, said bowl including an outer generally cylindrical portion and an inner inverted bowl portion associated therewith, a liner for said bowl and securing means for said liner, positioned in the space between said outer cylindrical portion of the bowl and said inner bowl portion, including lugs on said liner adapted to extend into the space between the cylindrical portion and the bowl portion, the bowl being apertured in line therewith and securing members positioned between the cylindrical portion and the bowl portion adapted to engage said lugs and means for exerting tension thereon.

2. In a crushing machine which includes a cone, a bowl about said cone, and means for imparting a gyratory movement to said cone, said bowl including an outer generally cylindrical portion and an inner inverted bowl

portion associated therewith, a liner for said bowl, and securing means for said liner, positioned in the space between said outer cylindrical portion of the bowl and said inner bowl portion, including lugs on said liner, the bowl portion being apertured in line therewith, and securing bolts adapted to engage said lugs.

3. In a crushing machine which includes a cone, a bowl about said cone, and means for imparting a gyratory movement to said cone, said bowl including an outer generally cylindrical portion and an inner inverted bowl portion associated therewith, a liner for said bowl, and securing means for said liner, positioned in the space between said outer cylindrical portion of the bowl and said inner bowl portion, including lugs on said liner, the bowl portion being apertured in line therewith, and securing bolts adapted to engage said lugs, and abutments for said bolts, in the space between the cylindrical portion and the bowl portion.

4. In a crushing machine which includes a cone, a bowl about said cone, and means for imparting a gyratory movement to said cone, said bowl including an outer generally cylindrical portion and an inner inverted bowl portion associated therewith, a liner for said bowl and securing means for said liner, positioned in the space between said outer cylindrical portion of the bowl and said inner bowl portion, including hook lugs on said liner, the bowl portion being apertured in line therewith, and U-bolts adapted to engage said lugs and abutments for said U-bolts, in the space between the cylindrical portion and the bowl portion.

5. In a crushing machine which includes a cone, a bowl about said cone, and means for imparting a gyratory movement to said cone, said bowl including an outer generally cylindrical portion and an inner inverted bowl portion associated therewith, a liner for said bowl and securing means for said liner, positioned in the space between said outer cylindrical portion of the bowl and said inner bowl portion, including lugs on said liner, the bowl portion being apertured in line therewith, and securing bolts adapted to engage said lugs, and abutment webs for said bolts, in the space between the cylindrical portion and the bowl portion.

6. In a crushing machine which includes a cone, a bowl about said cone, and means for imparting a gyratory movement to said cone, said bowl including an outer generally cylindrical portion and an inner inverted bowl portion associated therewith, a liner for said bowl and securing means for said liner, positioned in the space between said outer cylindrical portion of the bowl and said inner bowl portion, including lugs on said liner, the bowl portion being apertured in line therewith, and securing bolts adapted to engage said

lugs, and abutment webs for said bolts, in the space between the cylindrical portion and the bowl portion, the upper edges of said webs being downwardly and inwardly inclined toward the cone.

7. In combination with a crushing machine which includes a cone and means for imparting a gyratory movement thereto and a bowl member positioned about said cone, said bowl member including an inner inverted bowl portion and an outer and generally cylindrical portion, the two being connected at their lower edges, a liner for said inverted bowl portion, and securing means for said liner including lugs extending from the outer face of said liner intermediate top and bottom thereof, the inverted bowl portion being apertured to permit the penetration therethrough of said lugs, said lugs lying within the peripheries of the apertures through which they pass and being adapted to permit unimpeded vertical movement of the liner downwardly away from the face of the inverted bowl portion.

Signed at Chicago, county of Cook, and State of Illinois, this 29th day of September, 1928.

EDGAR B. SYMONS.
